UNITED STATES PATENT OFFICE.

CUSHING C. HARLOW, OF BROCKTON, MASSACHUSETTS, ASSIGNOR TO THE
HARLOW LUBRICATOR COMPANY, OF SAME PLACE.

LUBRICATOR.

SPECIFICATION forming part of Letters Patent No. 324,996, dated August 25, 1885.

Application filed December 15, 1884. (No model.)

To all whom it may concern:

Be it known that I, CUSHING C. HARLOW, a citizen of the United States, residing at Brockton, in the county of Plymouth, and State of Massachusetts, have invented certain new and useful Improvements in Lubricators; and I do hereby declare that the following is a full, clear, and exact description of the invention, which will enable others skilled in the art to which it appertains to make and use the same.

My invention relates to lubricators; and it has for its object to provide improved means for regulating the supply of the lubricant, and to so locate the devices for this purpose that they may be easily and conveniently operated.

A further object of the invention is to improve the details of construction of the lubricator for which Letters Patent No. 295,919 were granted me April 1, 1884, and to provide a device of this character which shall combine simplicity of construction with ease and efficiency of operation and durability in use.

With these ends in view, the invention consists in the improved construction and combinations of parts hereinafter fully described, and pointed out in the claims.

In the drawings, Figure 1 is an elevation of a lubricator constructed in accordance with my invention. Fig. 2 is a plan view of the same with the cap or cover removed. Fig. 3 is a vertical section on the line $x-x$, Fig. 2. Fig. 4 is a vertical section on the line $y-y$, Fig. 2. Figs. 5 and 6 are detail views, as will be more fully mentioned.

In the accompanying drawings, in which like letters of reference indicate corresponding parts in all the figures, A represents a suitable base, which is provided with an interiorly-threaded flange, a , which is adapted to receive the exteriorly-threaded end of the side a' , which is cylindrical in form and preferably of metal.

Extending downwardly from the under side of the base A is a neck, a^2 , which is exteriorly threaded to engage a threaded opening at the desired point for the attachment of

the lubricator. Said neck is also preferably provided with a flanged portion, a^3 , having angular sides for the reception of a wrench, by which means it may be firmly tightened to position.

Within the base A are provided upwardly-projecting posts a^4 , which extend from the bottom or floor of said base.

B represents rods having threaded ends, which ends are seated and held in place in the openings of the upwardly-projecting posts, a^4 , said rods extending a short distance above the upper end of the side a' . The said rods B, in conjunction with the side a' , serve to support a top piece, a^5 , which is provided on its inner side, near the lower end thereof, with a circumferential shoulder, a^6 , which shoulder rests and is supported upon the upper edge of the side a' . Said top piece is of a less circumference at its upper end than for its remainder or body portion, thus forming a circumferential seat or shoulder, a^7 , the purpose of which will appear more fully hereinafter.

Extending inwardly from opposite points on the interior of the top piece, a^5 , are bearing-castings b , which are provided with holes or openings for the passage of the upper ends of the rods B. The upper ends of said rods B are threaded, as shown, and fitting upon these ends are nuts b' , which are located, when tightened upon the threaded ends of the said rods B, in seats b^2 . It will thus be seen that when said nuts are tightened the cap-piece will be prevented from turning, and will also be held against displacement or accidental detachment from the side a' . The top piece, a^5 , and the bearing-castings are provided with registering openings, which serve as a bearing for a rock-shaft, b^4 , which extends across the reservoir. One end of said rock-shaft extends outside of and beyond the top piece, where it has attached to it in any convenient or suitable manner a rocker-arm, b^5 , which is adapted to be connected with any suitable moving part of the engine, by which means the said arm and shaft are oscillated to actuate the oil-feeding devices of the lubricator.

Upon the rock-shaft b^4 , between the two bearing-castings, is mounted a pinion, b^6 , which

in this case has outwardly-extending collars or sleeves b^1 , provided with holes or openings for the passage of pins, which pins pass through openings in the rock-shaft, and thus hold said pinion rigidly upon the rock-shaft.

Upon the inner side of the base, and preferably cast integral therewith, is a box or chamber, C, having threaded openings c^1 c^2 , located, respectively, upon the upper side of said box or chamber at the inner end wall thereof, and one (the opening c^3) in the side of the base, so as to communicate with the interior of said box, all of said openings being threaded.

15 Fitting in the opening on the upper side or top of said box is a tube, c^4 , threaded at its lower end. The upper end of said tube is reduced, and clamped upon said reduced upper end is a guide, c^5 , consisting of the sides c^6 , connected by the back wall or plate, thus leaving said guide open on its front side.

20 D represents a rack which has a sliding movement in the guide c^5 , and attached to said rack or formed integral therewith is a rod or piston, E, which is located in the tube c^4 , and is worked therein when the rock-shaft is oscillated to operate the rack D.

25 I have mentioned that the top piece was of a less circumference at its upper end than for its remainder or body portion; and fitting upon said upper end, and resting upon the seat or shoulder before mentioned, is a removable cap or cover, c^7 , which incloses and protects the working parts, and preventing the ingress of dust or other extraneous matter to the contents of the reservoir.

30 F represents a tube which is exteriorly threaded at its inner end, this end being adapted to engage the threaded opening c of the 40 box or easing and the base A.

35 Within the tube F is formed a valve-seat, d , which is conical in form, and adapted to fit the said seat is a valve, d^1 . The said valve d^1 is pointed or conical in shape to fit its seat d in the tube F, and is also contracted or smaller in diameter at said conical end than the diameter or bore in the main portion of the tube F, so as to form a passage around it and within the tube for the lubricant when the valve is unseated. The said contracted portion is provided 45 with an opening or series of openings for the passage of the fluid through it. The stem or body portion of the valve is tubular and fits in the tube F, which forms a guide for it in its movements from and to its seat, and a spiral spring, d^2 , serves to hold said valve in position with regard to its seat, the said spring resting at its lower end upon an annular shoulder, d^3 , within the sleeve or body portion.

50 60 For holding the spring in position I provide a screw nut or plug, d^4 , which fits the opening in the end of the tube F, and against which the outer end of said spring bears, said nut or plug being recessed on its inner end to receive the end of said spring, and thus hold it against displacement. The nut or plug is

also provided with a longitudinal opening for the passage of the lubricant.

Adapted to be attached to the end of the tube F is a pipe, d^5 , through which the lubricant may be carried to any point.

70 Fitting the opening c at the inner end of the box or easing C, and extending therefrom through an opening in the base A, in line therewith, is a tube, G, which is formed near its ends with shoulders e . Inclosing the said tube between the shoulders e , and bearing against the same with its ends, is a gauze or net cylinder, e^1 , which acts as a strainer and prevents foreign sedimentary or gritty matter from entering the valve in said tube, which I will now proceed to describe. The tube G is provided with a valve-seat, e^2 , valve e^3 , and spring e^4 , similarly constructed and arranged to the one already described located in the tube. The 80 lubricant, however, passes through an opening or openings in the tube G, being first strained by the gauze cylinder. A collar, f , is fitted upon the outer end of the tube G, and fitted upon said collar f is a supplemental 85 collar, f^1 . To control the flow of the lubricant through the tube G, I employ a valve, f^2 , which consists of a rod or stem, f^3 , adapted to fit the tube G. This rod or stem f^3 is provided at a suitable point upon its length with 90 a threaded portion, f^4 , which is adapted to engage threads upon the interior of the collar f . The end of said stem extends into the tube to a point adjacent to the openings in the same, and when it is desired to lessen the 95 flow of the lubricant through said openings the valve is turned, thus causing its end to advance further within the tube and close a portion of said opening or openings, whereby the quantity of lubricant allowed to pass 100 through said openings in a given time is decreased.

105 Upon the outer end of the stem f^3 is provided a disk, g , having a milled edge, in order that it may be more easily moved. The face 110 of said disk is provided with a series of figures or characters, as shown, which serve as a guide or index for operating the stem to control the flow of the lubricant.

115 The working parts of the lubricator before described are, with the exception of the rocker-arm, located within the reservoir, or so connected therewith as to be thoroughly lubricated.

120 The rocker-arm, as before described in my patent before referred to, is capable of being operated in any position by either a vertically or horizontally moving part of the engine.

125 Simplicity of construction and effectiveness of operation have been the chief points sought to be gained in constructing this device, and it will be seen from the above description, taken in connection with the accompanying drawings, that such are the advantageous features of my invention.

130 I claim as my invention and desire to secure by Letters Patent—

1. In a lubricator, the combination, with a reservoir, of the inlet-tube contained within the reservoir and extending across the same, and provided with the transverse openings 5 for the admission of the lubricant, an outlet-tube projecting from the reservoir, the inlet and outlet valves, respectively located and acting on a corresponding transverse plane within the inlet and outlet tubes, and a forcing-rod working between the ends of the said tubes at right angles to the movement of the valves, substantially as and for the purpose set forth.

2. In a lubricator, the combination, with a reservoir and the forcing-rod therein, an inlet-tube located within the reservoir and carrying the inlet-valve, an outlet-tube projecting from the reservoir and provided with the outlet-valve, and a valve-rod working through 20 the inlet-tube to regulate the supply of lubricant thereto, substantially as set forth.

3. In a lubricator, the combination, with a reservoir having the box or chamber C, of the inlet and outlet tubes provided with valves 25 and entering said box, the inlet-tube being contained within the reservoir and extending across the same, and provided with inlet openings, the valve-rod f^2 , working in the tube with respect to said openings to regulate the 30 supply of the lubricant thereto, and the forcing-rod working between the adjoining ends of the said tubes, substantially as set forth.

4. In a lubricator, the combination of the reservoir having the box or chamber C at one 35 end, the inlet-tube located across the reservoir at right angles to said chamber and entering the same, said tube being provided with inlet openings covered by a strainer, and with a valve between these openings and its inner 40 end, the outlet-tube extending from said chamber and provided with a valve, the forcing-rod working between the adjoining ends of the inlet and outlet tubes, and the adjustable

valve-rod f^2 , extending from the outside of the reservoir into the inlet-tube, the entire regulation of the flow of the lubricant being effected by the adjustment of said valve-rod with respect to the openings of the inlet-tube, substantially as set forth. 45

5. In a lubricator, the combination, with the inlet-tube located within the reservoir and provided with the openings and valve, and the forcing-rod for actuating said valve, of the adjustable valve-rod f^2 , working through 50 said tube with relation to the openings, substantially as and for the purpose set forth.

6. In a lubricator, the combination, with a reservoir, of the box or casing C within the same, the inlet and outlet tubes located on a corresponding horizontal plane and entering 60 said box on diametrically-opposite sides, the valves in said tubes, and openings in the inlet-tube, and the forcing-rod operating at right angles to the valves, and a regulating-rod working in the inlet-tube, substantially as and 65 for the purpose set forth.

7. In a lubricator, the combination, with a reservoir having a box or casing within the same and provided with the forcing-rod, of the inlet-tube having the openings in its shell, 70 and a strainer fitted around the tube and over said openings, substantially as set forth.

8. In a lubricator, the combination, with an inlet-tube located within the reservoir and having inlet-openings, of the regulating-valve 75 consisting of the screw-threaded stem working longitudinally in said tube and provided with an end disk having a graduated face, substantially as and for the purpose set forth.

In testimony whereof I affix my signature in 80 presence of two witnesses.

CUSHING C. HARLOW.
